(57) **CLAIM**

The ornamental design for a solid ink stick for an ink jet printer, as shown and described.

DESCRIPTION

FIG. 1 is a perspective view of a solid ink stick for an ink jet printer in accordance with the present invention;

FIG. 2 is a front view thereof;

FIG. 3 is a right side view thereof;

FIG. 4 is a rear view thereof;

FIG. 5 is a left side view thereof; and,

FIG. 6 is a top plan view thereof.

The broken lines immediately adjacent to the claimed areas represent the boundaries of the design. The broken lines showing portions of the ink stick illustrate environmental subject matter which forms no part of the claimed design.
